[57] CLAIM

The ornamental design for a dental articulator with a ball mounting, as shown and described.

DESCRIPTION

FIG. 1 is a top rear isometric view of a dental articulator with a ball mounting showing my new design; FIG. 2 is a front elevational view, the rear elevational view being a mirror image thereof; FIG. 3 is a right side elevational view; and FIG. 4 is a left side elevational view.

fig. 5

fig. 1

fig. 2

fig. 4

fig. 3

UNITED STATES PATENT AND TRADEMARK OFFICE
CERTIFICATE OF CORRECTION

PATENT NO. : Des. 286,179
DATED : October 14, 1986
INVENTOR(S) : Ronald E. Huffman

It is certified that error appears in the above-identified patent and that said Letters Patent are hereby corrected as shown below:

Kindly amend the description of the Figures 2-5 as shown below:

Figure 2 is a top view thereof;

Figure [2] 3 is a front elevational view, the rear elevational view being a mirror image thereof;

Figure [3] 4 is a right side elevational view thereof;
Figure [4] 5 is a left side elevational view.

Signed and Sealed this
Thirtieth Day of June, 1987
